US0D1061409S

(12) **United States Design Patent** (10) **Patent No.:** **US D1,061,409 S**
(45) **Date of Patent:** **** Feb. 11, 2025**

(54) **BATTERY**

(71) Applicant: **Brunswick Corporation**, Mettawa, IL (US)

(72) Inventors: **Matthew Z Seta**, Fond Du Lac, WI (US); **Robert A. Podell**, Slinger, WI (US); **Stephen R. Collins**, Fond du Lac, WI (US); **Todd D. Dannenberg**, Fond du Lac, WI (US)

(73) Assignee: **Brunswick Corporation**, Mettawa, IL (US)

(**) Term: **15 Years**

(21) Appl. No.: **29/823,701**

(22) Filed: **Jan. 19, 2022**

(51) LOC (15) Cl. **13-02**

(52) U.S. Cl.

USPC **D13/103; D13/107**

(58) **Field of Classification Search**

(57) **CLAIM**

The ornamental design for a battery as shown and described.

DESCRIPTION

FIG. 1 is a front perspective view of a battery according to our new and ornamental design;

FIG. 2 is a side view thereof;

FIG. 3 is an opposite side view thereof;

FIG. 4 is a front view thereof;

FIG. 5 is a rear view thereof;

FIG. 6 is a top view thereof; and,

FIG. 7 is a bottom view thereof.

The broken lines illustrate portions of the battery that form no part of the claimed design.

1 Claim, 7 Drawing Sheets
